UNITED STATES PATENT OFFICE

RICHARD C. COUPLAND, OF THE UNITED STATES ARMY, NORFOLK, VIRGINIA

AMMUNITION FEED BOX

Application filed April 16, 1931. Serial No. 530,583.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 The subject of this invention is an ammunition feed box especially applicable for machine guns mounted on aircraft or land vehicles where space is extremely limited and the gunner is obliged to position the box 10 with one hand.

The present invention is designed particularly as an improvement over the box shown in Patent No. 1,799,283, issued April 7, 1931. In this type of box a slidable cover carries 15 a feed pawl for advancing the cartridge belt into the feedway of the gun.

The improvements are directed essentially to the provision of an exit which will support two cartridges, of a sliding connection 20 between the cover and box that will house means for holding the cover in place, and of means for confining the cartridges to the box when the cover has been moved to the loading 25 position. In addition there is provided a novel method of securing the feed box in a support.

With the foregoing and other objects in view, the invention resides in the novel arrangement and combination of parts and in 30 the details of construction hereinafter described and claimed, it being understood that changes in the precise embodiment of the invention herein disclosed may be made within the scope of what is claimed without departing 35 from the spirit of the invention.

A practical embodiment of the invention is illustrated in the accompanying drawings, wherein:

40 Fig. 1 is a view in side elevation of the improved ammunition feed box, mounted in its support, parts being broken away to show the normal position of the end rounds of the belt.

45 Fig. 2 is a plan view of the box of Fig. 1. Fig. 3 is a view in side elevation parts be-

ing broken away and showing the belt advanced into the feedway of a machine gun.

Fig. 4 is a plan view of Fig. 3.

Fig. 5 is a fragmentary view in front elevation of the box.

Fig. 6 is a sectional view on the line 6—6 of Fig. 4.

Referring to the drawings by numerals of reference:

The ammunition feed box 5 is in the form 55 of a rectangular open carton of light metal or water-proof fiber-board adapted to contain a belt of ammunition 6. The front wall 7 which is adjacent the gun 8 when the box is placed in the support 9 is terminated short 60 of the top of the box to provide an exit 10, the dimensions of which are substantially equal to a cartridge 11. The upper margin of the front wall is formed into a transverse groove 12 adapted to receive a lug 13 of the 65 support when the box is moved laterally through the action of the spring 14, carried by the outer wall 15 of the support 9. By virtue of this engagement the box is firmly held in place but may be readily removed. 70

A guide plate 16 secured to the inside of the wall 7 to cover the internal projection of the groove 12 is turned outwardly to form a shelf 17 constituting the floor of the exit 10 and projecting beyond the side wall 7 so that 75 when the box is in position the shelf is inserted in the feedway 19 of the gun and overlies the floor 18. The shelf is of sufficient depth to support two cartridges, and includes perpendicular sides 20 (Fig. 5) having angularly disposed upper ends 21 parallel to the shelf to restrict the mouth of the exit to the size of a cartridge. The inside corners 22 of the ends 21 are flared upwardly 80 to insure a smooth delivery of the cartridges to the mouth of the exit. The shelf is receivable in the feedway 19 of the gun and the spacing between the ends 21 enables the feed pawl 19a of the gun to be reciprocated without interference. 85 90

The cover 23 of the feed box is conveniently mounted for sliding movement by means of a tongue and groove connection (Fig. 6). In the present instance the tongue 24 is formed by turning the upper edge of the side plate 25 of the container over upon itself and the groove 26 is provided by complementarily channeling the sides of the cover.

The tongue 24 houses a spring 27 carrying a stud 28 whose rounded head protrudes through an aperture 29 in the tongue and is selectively engageable in apertures 30—30 in the groove member 26 of the cover, to respectively hold the cover in the normal position shown in Fig. 1 and in the loading position shown in Fig. 3. A finger 31 (Figs. 4 and 5) at the inner end of one of the groove members is engageable with the corresponding end of the tongue to prevent movement 20 of the cover away from the gun beyond the prescribed normal position.

Referring to Fig. 2, the cover is of less length than the opening of the feed box and the front side is provided centrally with a recess 32 in rear of which is a transverse depression 33. This depression accommodates the joint 34 of a hinge member, the fixed leaf 35 being secured to the cover by means of rivets, and the loose leaf constituting a belt 30 advancing pawl 36 overlying the recess 32 and having a depending extremity 36a normally positioned in rear of the second cartridge of the belt. A torsion spring 37 mounted on the pivot pin of the joint 34 exerts sufficient pressure on the pawl 36 to insure retention of the two end rounds in the exit 10 and to prevent accidental withdrawal of the belt.

The rear wall 38 of the feed box is terminated short of the top of the box to accommodate an apron 39 provided on the rear end of the cover in continuation of a rib 40. A large bearing surface for the hand of the operator is obtained by this structure which 45 also serves to strengthen the edge of the cover.

The upper edge of the rear wall 38 of the box is likewise reinforced by a transverse rib 41 terminating in the wings 42 extending 50 along the side walls parallel to and below the cover and serving to confine the cartridges to the box when the cover has been moved to the loading position as seen in Figs. 3 and 4.

The requirements always emphasized in an 55 ammunition box for aircraft guns are rapidity and facility of applying the box to the gun and these are met in the box of this invention. The operation of applying the box 5 consists in grasping it with the left hand, 60 lowering it into the support 9, allowing it to be moved laterally by the spring 14 to insert the exit in the feedway of the gun and moving the cover 23 to the right to advance the end cartridge into position to be withdrawn by the bolt. All of this is accom-

plished by an uninterrupted effort without releasing the box or changing the position of the hand relative to the box. Furthermore by having the pawl 36 engaged behind the second round in the exit of the box inserted 70 within the gun and by having the loading movement of the cover position the end cartridge in line with the bore of the barrel makes the end cartridge immediately available to the extractor of the bolt so that the bolt need be operated only once to load the gun.

With the cover of the feed box in the loading position, the cover of the gun may be raised for the purpose of gaining access to the bolt to clear stoppages without fear of losing the belt or disarranging the belt or the end cartridges because the pawl will hold the belt in the feedway 19 of the gun. The pawl also prevents the belt from falling back 85 into the box.

The machine gun is illustrated as being mounted on a cradle 43 pivotally carried by a standard or yoke 44. The support 9 is secured to the cradle by screws 45, only one of 90 which is shown in Fig. 1.

I claim.

1. The combination with a machine gun having a cartridge feedway, a support adjacent the feedway of the gun, a lug on the 95 side of the support next to the gun, and a spring on the side opposite the lug, of an ammunition feed box insertable in the support and movable laterally to be engaged by the lug on the support, said feed box having a projecting mouth insertable in the feedway of the gun.

2. The combination with a machine gun having a cartridge feedway, a support adjacent the feedway of the gun, a lug on the side 105 of the support next to the gun, and a spring on the side opposite the lug, of an ammunition feed box insertable in the support and movable laterally to be engaged by the lug on the support.

3. The combination with a machine gun having a cartridge feedway, of an ammunition box supported adjacent the feedway and adapted to contain a belt of cartridges, an exit in the box positioned to register with the 115 feedway and having a floor of sufficient width to support two cartridges, a cover slidable on the box, and a feed pawl carried by the cover and normally positioned opposite the inside edge of the floor of the exit, whereby two cartridges are advanced ahead of the pawl when the pawl is moved to feeding position thereby placing the end cartridge of the belt in engagement with the extractor of the gun.

4. The combination with a support having a lug on one side and a spring on the other side, of an ammunition feed box insertable in the support and having an exit, one wall of the box having a groove below the exit 120 adapted to receive the lug when the box is

- moved laterally by the spring of the support, and a guide plate secured to the inside of said wall below the groove and turned over to form the floor of the exit. 70
- 5 5. An ammunition feed box comprising a container having a cartridge exit at the upper end of its front wall, a shelf constituting the floor of the exit and projecting within and without the wall, the width of the shelf dimensioned to support two cartridges, the shelf having perpendicular sides with ends turned over parallel to the shelf to restrict the mouth of the exit, and the inside corners of the turned over ends being flared. 75
- 10 15. An ammunition feed box comprising a container having a cartridge exit at the upper end of its front wall, a shelf constituting the floor of the exit and projecting within and without the wall, the shelf having perpendicular sides with ends turned over parallel to the shelf to restrict the mouth of the exit, and the inside corners of the turned over ends being flared. 80
- 15 20. 6. An ammunition feed box comprising a container having a cartridge exit at the upper end of its front wall, the upper portion of each side wall turned over upon itself to form a tongue having an aperture in its outside wall, a cover having channeled sides 85
- 25 forming grooves members fitting on the tongues, the outside wall of the groove formed with apertures, a spring housed in the tongue, a stud on the spring protruding through the aperture in the tongue and engageable in the apertures of the groove members, and a feed pawl carried by the cover and disposed in the exit. 90
- 30 35. 7. An ammunition feed box comprising a container having a cartridge exit at the upper end of its front wall, the upper portion of each side wall turned over upon itself to form a tongue having an aperture in its outside wall, a cover having channeled sides 95
- 40 forming grooves members fitting on the tongues, the outside wall of the groove formed with apertures, a spring housed in the tongue, a stud on the spring protruding through the aperture in the tongue and engageable in the apertures of the groove members, and a feed pawl carried by the cover and disposed in the exit. 100
- 45 50. 8. An ammunition feed box comprising a container, the upper portion of each side wall turned over upon itself to form a tongue having an aperture in its outside wall, a cover having channeled sides forming groove members fitting on the tongues, the outside wall of the groove formed with apertures, a spring 105
- 55 housed in the tongue, a stud on the spring protruding through the aperture in the tongue and engageable in the apertures of the groove members. 110
- 60 65. 9. An ammunition feed box comprising a container the upper portion of each side wall turned over upon itself to form a tongue, a cover having grooved sides fitting on the tongues, and means housed within the tongue and protruding therethrough to engage the grooved side of the cover. 115
- 65 70. 10. An ammunition feed box comprising a container having a cartridge exit at the upper end of its front wall, a cover slidable on the container and having a transverse depression, a hinged member having its joint disposed in the depression, the movable leaf of the hinge member constituting a cartridge feed pawl and having a depending extremity movable through the exit. 120
- 70 75. 11. An ammunition feed box comprising a container, a cover slidable on the container, and a transverse reinforcing rib on the upper edge of the rear wall, said rib terminating in wings extending along the side walls below the cover. 125
- 75 80. 12. An ammunition feed box comprising a container, a cover slidable on the container, and wings extending along the inside walls of the container below the rear end of the cover. 130
